Patented Oct. 27, 1914.

UNITED STATES PATENT OFFICE.

HANS WERWATH, OF CHICAGO, ILLINOIS.

AWNNG.

1,114,952.

Specification of Letters Patent. Patented Oct. 27, 1914.

Application filed March 4, 1914. Serial No. 822,344.

To all whom it may concern:

Be it known that I, HANS WERWATH, a citizen of the United States of America, residing at Chicago, in the county of Cook and State of Illinois, have invented certain new and useful Improvements in Awnings, of which the following is a specification.

My present invention relates to improvements in awnings and is particularly designed to provide a simplified supporting frame for the awning.

The primary object of the invention is to simplify the construction and operation of window and similar awnings, by fashioning adjustable guide arms or brackets which are operable and co-act with the awning as it is raised or lowered.

The invention consists essentially in certain novel combinations and arrangements of parts as hereinafter set forth and pointed out in the appended claims.

In the accompanying drawings I have illustrated one complete example of the physical embodiment of my invention constructed according to the best mode I have so far devised for the practical application of the principles of the invention.

Figure 1 is a sectional view through a window showing the application thereto of my invention. Fig. 2 is an outside view of the window of Fig. 1 with the awning fixtures attached. Fig. 3 is an enlarged view of one of the awning brackets or guide bars of the supporting frame. Fig. 4 is an edge view of Fig. 3. Fig. 5 shows an automatic locking device employed to hold the movable portion of the bracket in the extended position assumed when the awning is in operative position. Fig. 6 is an edge view of Fig. 5. Fig. 7 is a diagrammatic view showing the awning when in lowered position.

In the preferred embodiment of my invention I employ two stationary brackets as 1 and 2 attached to the right and left sides of the window frame 3 by means of the flanges or lugs 4 located at either end. These brackets are made in pairs and are duplicates, except that one may have a perforation, and the other an open slot as 5, as bearings for journaling the pins 6 upon which the roller 7 turns. The roller is journaled near the top of the brackets and is adapted to revolve on its bearing pins 6 in the bearings, and a shade or awning of usual

or suitable material indicated by the numeral 8 is adapted to be wrapped or rolled about the roller. It will be understood that the roller is suspended and free to revolve in its bearings and a cord or cable 9 which is wound around the drum 10 on the roller in the opposite direction to the winding of the curtain or awning, is employed to operate the roller and through it the awning. The cable is brought through a suitable opening in the wall of the building, passed over a sheave 11 and may be attached to a cleat 12 as shown, so that the awning may be operated from the interior of the building without opening the window as will be understood.

At the lower free end of the awning or curtain a weighted bar 13 is attached which performs the functions of holding the awning taut at all times and also acts as a guide and retainer when the awning is being lowered or raised.

In Fig. 3 is shown the right bracket 1 and inasmuch as the left bracket is similar in construction a detail description of this bracket 1 will suffice for both brackets. The stationary portion of the bracket is slotted at 13' forming two forks 14 and 15, and while the slot 13' is open at the bottom it will be seen that it is provided with an enlarged opening 16 at its upper end. The slot is for the guidance and passage of the end of the weighted bar 13 which is adapted to travel up and down in the slot 13'. In connection with the weighted bar I employ a traveling retainer rod 17 which has a movement limited to the length of the slot 13'. This rod has at each end a forked locking member 18, outside the bracket and provided with end recesses 19, 19 for a purpose to be described.

In connection with the bifurcated or forked section of the bracket I employ an oscillatable or swinging section 20 which is pivoted at 21 by a pin to the bracket 1, and by means of a second pin 22 movable in the guide slot 23 in the fork 14 the radius of the swinging or oscillation of the section is limited. This section is also provided with a slot as 24 forming a continuation of the slot 13' and at its lower end the section 20 is enlarged to provide a space for the heart shaped plate 25 which is fixed by a bridge plate 26 to the section 20 in proper position, because of its size and shape, to form a loop 110

in the slot which at its end is closed by means of the spring detent 27. The loop 28 at its extreme end is bounded by a wall 29 which forms a cam face or edge and the plate 25 is fashioned with a bearing edge 30 extending each side of the ridge or apex 31 of the cam face 29, and this edge is the contact point when the bracket section is being raised as will be described. Below this bearing or contact edge and at the side of the apex 31 opposite the cam 29 a second cam face 32 is provided, and then the loop returns to the slot 24 by way of the gate or detent 27.

At 33 a notch is provided for the reception of the retainer rod 17 and this notch or recess is located near the lower end of the slots 13' in the wall of the forked brackets 1 and 2.

It will be understood of course that practically all the parts of the brackets and operative parts are of metal, and the parts of suitable size, shape and dimensions.

In operation, when it is desired to lower the awning from the position of Figs. 2, 3, 4, for instance, the cord 9, is loosened from the cleat 12 in Fig. 1 and is permitted to slip through the hand as the weighted bar 13, by gravitation, falls and causes the awning to unroll from the revolving roller 7. As the roller revolves it winds the cord on the drum 10. The weighted bar 13 descends through the slots 13' and the retainer rod 17 with the automatic locking devices 18 also travels with the bar, but when the bar reaches the lower end of the slot 13' the notches or recesses 19 of the locking members 18 engage the two pins 21 and 22 and the movement of the retainer rod is stopped.

The weighted bar however continues its descent into and through the slots 24, passing over the detents 27 and into the loops 28 of the oscillatable brackets. The weighted bar gradually passes around the first turn of the loop and is halted at the cam edge 29. The cord 9 is now drawn upon, the roller is started to revolve, but the weighted bar is lifted in direct contact with the lifting edge 30 of the plate 25 and as the pull on the cord 9 continues and the rolling or winding of the roller is impeded, the result is that the oscillatable bracket is swung on its pivot pins 21 to the dotted position in Fig. 3 and guided by the pins 22 in the slots 23. The cord is now tied to the cleat 12 and the load of the brackets and extended awning is taken at the edges 30 of the plate 25. It will be remembered that the recesses 19 of the locking members 18 are engaging the pins 21 and 22, but during the swing of the brackets the retainer rod 17 has been brought to the position in Fig. 5 where it is seated in the notches 33, and this rod has also retained the upper half of the awning in a vertical plane as in Fig. 7, while the lower half has

swung out with the oscillating brackets with the rod 17 as a pivot point. In this manner the desired angle and shape to the lowered awning is secured. It will be understood of course that this angle and shape may be varied by changes in dimensions and locations of parts and such changes are contemplated.

When it is desired to raise the awning, the cord is loosened and the brackets with the weighted bar swing back to the full position of Fig. 3. The brackets may swing back by gravity, and the cord is held taut so that when the brackets arrive at the position in Fig. 3 the weighted bar falls from the edge 30 down upon the cam edge 32. A continued hauling of the cord now revolves the roller 7 and the awning is wound upon the roller, the weighted bar travels up the return side of the loop 28, forces its way past the spring detent 27, into the slot 24, through this slot into the slot 13' where it picks up the retainer rod 17 and with said rod is lifted to the top of the slot 13' the rod being carried into the enlarged opening 16. The cord is now secured to the cleat 12 and the awning is thus held in raised position.

Having thus fully described my invention what I claim is:

1. The combination with a pair of stationary brackets, and a rolling awning supported and guided therein, of movable bracket sections connected thereto and adapted to extend, support and retain a portion of the awning when lowered, and means for releasing the awning preparatory to being raised.

2. The combination with a pair of stationary brackets and a rolling awning supported and guided therein, of a pair of movable bracket sections adapted to support and hold the awning when lowered, and means for automatically releasing the awning so that it may be raised.

3. The combination with a pair of slotted stationary brackets and a rolling awning journaled therein and guided by said brackets, of movable bracket sections having complementary slots and a loop portion to said slots whereby the awning may be held in lowered position, or automatically released for raising as described.

4. The combination in an awning structure of a pair of pivoted slotted sections adapted to guide a moving awning and means for moving said sections in unison, said slotted sections having a loop portion whereby the awning may be held in lowered position, or automatically released for raising as described.

5. The combination in an awning structure of a pair of pivoted slotted sections adapted to guide a moving awning, said slotted sections having a loop portion and a

contact point for actuating means to swing said sections and the awning, and automatic means for releasing the actuating means for raising the lowered awning.

5 6. A slotted awning section formed with a return loop, a guide plate within the loop, and means for causing an actuating member to engage said plate as described.

10 7. A slotted awning frame section formed with a return loop, a guide plate within the loop having a contact point for an actuating member, means in the loop for guiding said member to said point, and means for guiding said member from and beyond said

15 point for the purpose described.

20 8. A slotted awning bracket formed with a return loop and a spring gate closing the return end of said loop, a guide plate within the loop, and means for guiding a moving actuating member to said guide plate, as described.

25 9. A slotted awning bracket having a return loop and a guide plate therein having a contact point for an actuating member, a cam edge in the loop for guiding said member to the point, and a cam edge for guiding said member through the loop when freed from said point.

30 10. In an awning structure the combination with a movable awning a stationary bracket and a movable bracket, of a retainer rod moving with the awning and means on

said rod engaging the movable bracket to hold the awning as described.

11. In an awning structure the combination with a movable awning a stationary bracket having a pivot pin and a guide pin, of a retainer rod moving with the awning and means on said rod for engaging said pins to hold said rod in operative position. 35

12. In an awning structure the combination with a movable awning, a stationary bracket having a pivot pin and a guide pin, of a retainer rod movable with the awning, recessed forks on said rod to engage said 45 pins, and a notch in the stationary bracket for said rod, for the purpose described.

13. The combination with a pair of slotted stationary brackets and a pair of complementarily slotted oscillatable brackets pivoted thereto, of a rolling awning journaled in the stationary brackets, a weighted bar on the awning movable through the slotted brackets, and means whereby said bar may be used to swing the oscillatable brackets 55 and a part of the awning with relation to the stationary brackets and remainder of the awning.

In testimony whereof I affix my signature in presence of two witnesses.

HANS WERWATH.
